UNITED STATES PATENT OFFICE.

JOHN T. SCOTT, CHARLES G. HIGHTOWER, AND FRANK E. NEITZEL, OF SAN FRANCISCO, CALIFORNIA.

METAL-BENDING MACHINE.

SPECIFICATION forming part of Letters Patent No. 653,704, dated July 17, 1900.

Application filed January 9, 1900. Serial No. 821. (No model.)

To all whom it may concern:

Be it known that we, JOHN T. SCOTT, CHARLES G. HIGHTOWER, and FRANK E. NEITZEL, citizens of the United States, residing in the city 5 and county of San Francisco, State of California, have invented certain new and useful Improvements in Metal-Bending Machines; and we do hereby declare the following to be a full, clear, and exact description of the same.

10 The present invention relates to a machine for the bending of metal generally, although designed more especially for the bending of tubes to be used in connection with water-tube boilers; and it consists in the arrangement of parts and details of construction, as will be hereinafter fully set forth in the drawings and described and pointed out in the specification.

15 The object of our invention is to provide a machine whereby the tubes, rods, or metal plates may be bent into irregular shapes, curves, or compound curves in such manner as to considerably increase the output over machines generally employed for such purpose, at the same time simplifying the work 20 of bending and reducing the help ordinarily required to carry out the work of bending. Thus the output of finished material is not only materially increased, but the cost of 25 bending considerably reduced, which is a feature where the material is to be used in connection with work to be performed within a specified time.

30 To comprehend the invention, reference should be had to the accompanying sheets of drawings, wherein—

35 Figure 1 is a top plan view of the bender, the normal position of the swinging arm being shown in dotted lines. Fig. 2 is a detail 40 view of the swinging arm in side elevation. Fig. 3 is an enlarged longitudinal sectional view, in side elevation, of the swinging arm; and Fig. 4 is a horizontal sectional bottom plan view taken on line $\alpha\alpha$, Fig. 3.

45 In the drawings the letter A is used to indicate the bed-plate, having a center post B rigidly secured thereto. Upon this post works hub C² of the swinging slotted arm C, which arm at its outer end carries the depending 50 enlarged head C'. Within the slotted portion

of the swinging arm is fitted the slide-block D, said block carrying the spindles E and G. The slide-block is held in place within the slotted arm C by any suitable means. Spindle E is formed with an eccentric portion E', 55 on which is fitted forming-roller F. This roller works against face of curved former F', bolted to the bed-plate, against which the bar, rod, plate, or tube being bent or shaped is pressed. It will be understood that the former 60 F' is shaped to the form into which the bar, rod, plate, or tube is to be bent. To the lower end of spindle G is secured the roller H, which roller during the working of the machine contacts with the cam or back former 65 I, secured to the bed-plate, used for the production of compound curves. The forming-roller F is held against the former F' by means of the swinging arm K, said arm being pivoted to bolt I', which bolt holds adjustable 70 collar K' in slotted arm C. Arm K is held against spindle G by pressure of spring K², which spring is secured and coiled about pin a, depending from arm K, and secured at its opposite end to washer a' of bolt I'. The tension of this spring holds the swinging arm against spindle G and presses said spindle inward and holds the slide-block D against 75 outward movement. As said slide-block carries spindle E, upon which forming-roller is 80 mounted, the forming-roller will be held pressed against the former. The slide-collar is given adjustment through the medium of the adjustable rod or keeper J, interposed between said collar and end wall of slotted arm. 85

To the bed-plate A at any suitable point within the described path of the swinging arm is attached the dog L, with which the pin a contacts during the movement of the said arm.

The lower end of the enlarged or depending head C' of the slotted arm C rests upon the upper face of rack M, attached to bed-plate. This rack is in the form of an arc and is engaged by spur-gear M', secured to lower end of shaft M², extending through an opening in the head C'. Upon this shaft above the head is loosely fitted the bevel-gear N, having a conical friction ring or hub N' upwardly projecting therefrom. Said gear is held in place by the collar b, secured upon 95 100

the shaft within the conical friction ring or hub. This bevel-gear meshes with and is driven by pinion N^2 , attached to outer end of drive-shaft O, which shaft works in bearings 5 O', bolted to the slotted arm C.

To the shaft M^2 is secured by feathers b' the cone friction or clutch P, which engages the conical hub or ring N' of gear N. The friction is raised or lowered by the nut P' 10 working upon the screw-threaded portion d of the shaft M^2 . Connection is made between the nut P' and the friction or clutch P by means of the collar Q, secured to and depending from the said nut, which collar is held to 15 the friction or clutch by the collar d', secured to upper end of said friction or clutch. Being thus secured, it is obvious that as the nut is loosened or tightened upon the shaft M^2 the friction or clutch P will be raised or lowered upon the shaft, the vertical movement thereof being sufficient to place the same out of or in frictional engagement with the conical hub or ring of the gear N. The nut P' is tightened or loosened by means of the handles Q', secured to and projecting therefrom. 20

Near the pivoted end of the slotted arm C is attached a dynamo or drive-motor Q ^{2} , the shaft Q ^{3} of which is connected with gear R, secured to drive-shaft O by gear R'. The motion of the motor is thus transmitted to drive-shaft O and the operative parts connected thereto and carried by the swinging arm C. 25

In order to remove friction between the head of the swinging arm and rack M, the said head is connected thereto by the keeper-rolls f f', suspended in bracket f ^{2} , attached to rear wall of the head. These rolls hold the head to the rack and at the same time relieve the machine of undue friction, which 30 would result in case the head were permitted to bear directly upon the rack.

The hub C ^{2} of the swinging arm carries the quadrant S, to which is attached chain, rope, or cord S'. This chain, rope, or cord passes 45 over sheave T, held in bracket T', extending through an opening in bed-plate, and to the end thereof is attached weight T ^{2} . During the outward stroke or swing of the arm C' the chain, rope, or cord is wound upon the quadrant until the arm has made its full swing and become locked at the end of its stroke, as 50 will be hereinafter explained. As the rope, chain, or cord winds upon the quadrant the weight T ^{2} is raised. This weight is sufficient, 55 the moment the swinging arm is released, to return the arm to its normal position or starting-point X.

At the outer end of the swinging arm is carried a hinged catch g, which upon the completion of the stroke of the swinging arm engages the spring-pressed slide-bolt g', working through bracket U, located at the outer end of rack M. The moment the swinging arm has completed its stroke catch g moves 60 into locked engagement with the slide-bolt g', while at the same time nut P' is raised or loosened by one of the handles Q' striking

against the bracket U. As the arm continues its movement for a short while after arm engages the bracket, the pressure thereon 70 will turn the handle and unscrew the nut P'. Inasmuch as the threads d are cut at a heavy pitch this turn or part throw of the handles is sufficient to unscrew the nut and raise or elevate the friction or clutch P through its 75 described connections, so as to remove the same from frictional engagement with the conical hub N' of gear N. Connection between the drive mechanism and the shaft M^2 being thus broken, rotation of the said shaft 80 ceases.

From slide-bolt g' extends the cord U', which passes over pulley h and terminates at a point within convenient reach of the operator. By simply pulling upon this cord the 85 slide-bolt is drawn inward, so as to release the catch g. The moment this catch is released the weight T ^{2} descends and returns swinging arm to its starting-point. As the slide-bolt g' is held outward by pressure of 90 spring h', the moment the operator releases cord U' the slide-bolt is moved outward to be in position to be engaged by the catch g upon the next stroke of the swinging arm.

Spindles E and G are connected by brace- 95 plates G', which plates not only serve to hold spindles together at their lower end, but also to hold the forming-roller F in place.

The swing or outward movement of the arm K is limited by the stop or pin k, depending 100 from adjustable block D. Consequently the movement of said arm ceases when placed in line with spindle G, Fig. 3.

To the upper end of shaft M^2 is attached one end of tension-spring V, the opposite end 105 of which is connected to nut P'. The object of this spring is to hold the nut P' against accidentally working downward during the return movement of the swinging arm in order to provide against the friction or clutch P 110 engaging with conical hub of gear N.

1 and 2 indicate hydraulic cylinders attached to the bed-plate. Piston 3 of cylinder 1 carries form 4, while piston 5 of cylinder 2 carries yoke 6, to which forms 7 7' are secured. Form 4 registers with back form 8. It will be understood that the face of each form corresponds with the shape to be given to the pipe, tube, rod, or plate 10 inserted therebetween. Each form is removable. 115 Hence they may be varied in accordance with the shape to be given to end of tube, rod, or plate to be acted upon by the hydraulic press. The back forms 8 9 are held in place by end blocks 11 12. To the forms 7 7' are adjustably connected the stops 13, which stops engage or contact with projections 14 of block 12 and by their adjustment limit the stroke of yoke 6, the pressure thereon being released by means of the dog 15, connected to plunger 130 of cylinder 2 and center of yoke 6. Water-pressure is conveyed by pipe 16 to valve-coupling 17, the opening and closing of which is controlled by handle 18. Connection is 125

made between the valved coupling and cylinders 12 by means of the supply-pipes 19 and 20 and by exhaust-pipes 21 22.

The operation of the hydraulic press will 5 be readily understood without detail description thereof. If the machine is to be used for the bending of tubes or rods, the faces of the forms are grooved, and the former F' is provided with groove 25 and forming-roller 10 F with groove 26, within which the tube rests as bent into the required shape. By forming two grooves in each part the machine may be utilized to shape two tubes, pipes, or rods at the same time.

15 In operation the tube or article to be formed is inserted between the forms of the press, its end resting against block 27. The air is then admitted to the cylinders in order to close the forms and shape the tube there- 80

20 tween as required. At the same time the operator turns handles in order to screw down nut P' upon shaft M², so as to place friction or clutch P into frictional engagement with conical hub N' of gear N. Motion of drive- 90

25 shaft O, driven by motor Q, is thus imparted to shaft M² in order to drive spur M'. This spur intermeshing with rack M travels there- 95

upon and causes the arm C to swing outward.

As this arm swings outward the forming- 100

30 roller F bears upon and forces the tube against the former F', so as to shape the same there- 105

over, the curve of said former being that to be given the tube. The forming-roller is held 110

against outward movement during the opera- 115

35 tion of bending by means of the lock-arm K.

In case compound curve is to be given the 120

tube, then within the path of the swinging

arm in line with roll H is located the cam or 125

back former I at proper place. If the curve

40 to be given is an inwardly one, then the roller 130

H as it rides upon the curved cam or back

former forces the slide-block D, carrying the 135

forming-roller, inward in order to force the

forming-roller against the former. Should, 140

45 however, the curve to be given the tube at

such point be an outward one, the arm K is 145

released by the pin a depending there- 150

from engaging or coming into contact with

dog L, the pressure thereon being sufficient 155

50 to overcome pressure of spring K and to

swing the arm outward or away from spindle 160

G, said spindle having been previously moved

slightly inward in order to release the arm 165

by roller H bearing upon cam or back former.

55 When thus released, the slide-block D is 170

permitted to move outward in order to adjust

the forming-roller to the change in the bend 175

to be given, said slide-block being held in

proper place by the back former or cam 180

60 against which the roller H bears. The shape 185

of the back former or cam corresponds with

any change made in the former F'. Hence 190

the slide-block is automatically moved upon

the swinging arm in order to adjust the posi- 195

65 tion of the forming-roller. By this means ir- 200

regular curves may be given the tubes in

one operation instead of making each change

a distinct operation. As the swinging arm reaches the end of its stroke one of the handles Q' strikes against the bracket U and im- 70

parts sufficient turn to nut P' to raise same upon shaft M² and remove friction or collar P from frictional engagement with conical hub N' of gear N. Rotation of shaft M² 75

ceases and swinging arm remains stationary, 80

although drive-shaft O continues its work- 85

ing. As the swinging arm comes to rest, catch g engages slide-bolt g' and holds the 90

swinging arm locked against return stroke, in which position it remains until released 95

by the operator pulling upon cord U' in order to draw the slide-bolt g' out of engagement

with clutch g. When thus released, the 100

swinging arm is returned to its original po- 105

sition or starting by the descending or down- 110

ward travel of weight T².

Having thus described our invention, what we claim as new, and desire to secure protec- 115

tion in by Letters Patent, is—

1. In a bending-machine, the combination 90

with the bed-plates of an arm swinging there- 95

on, a former secured to the bed-plate, a form- 100

ing-roller carried by the swinging arm, said 105

roller coacting with the former, a curved rack 110

attached to the bed-plate, of a drive-shaft 115

working upon the swinging arm, a pinion car- 120

ried by said shaft engaging a gear loosely 125

mounted upon a shaft extending through the 130

swinging arm, a spur-gear attached to the 135

lower end of the vertical shaft and engaging 140

the rack, of a friction secured to the said shaft, 145

and of means for automatically placing the 150

friction in or out of frictional engagement 155

with the gear driven by the drive-shaft.

2. In a bending-machine, the combination 160

with the swinging arm, of the drive-shaft 165

working thereon, a forming-roller adjustably 170

secured to the swinging arm, a former with 175

which the said roller coacts during the opera- 180

tion of bending, a shaft extending vertically 185

through the swinging arm, a gear attached 190

to the lower end thereof, a rack with which 195

said gear meshes, and of means by which the 200

vertical shaft is placed in or out of operation 205

with the drive-shaft.

3. In a bending-machine, the combination 115

with the swinging arm, of a forming-roller car- 120

ried thereby, of a former with which it coacts 125

during the operation of bending, a device by 130

which the forming-roller is held in locked 135

position against outward movement and of 140

mechanism for imparting travel to the swing- 145

ing arm.

4. In a bending-machine, the combination 150

with the swinging arm, of a shaft extending 155

vertically through the outer end thereof, a 160

gear secured to the lower end thereof, a curved 165

rack with which the gear engages, drive mech- 170

anism carried by the swinging arm, and of 175

means by which the vertical shaft is placed 180

in or out of locked engagement with the drive 185

mechanism.

5. In a bending-machine, the combination 190

with the bed-plate, of a swinging arm secured 195

thereon, a forming-roller carried by the swinging arm, a former with which the forming-roller coacts attached to the bed-plate, of devices for moving the forming-roller toward 5 or from the former during the travel of the swinging arm, and of mechanism for throwing the swinging arm back and forth.

6. In a bending-machine, the combination with the bed-plate, of a former attached there-10 to, a swinging arm secured to the bed-plate, of means for imparting travel thereto, a forming-roller adjustably secured to the swinging arm, said roller coacting with the former, a swinging lock-arm for holding the roller 15 against outward movement, and of devices for automatically releasing the lock-arm so as to permit of the forming-roller adjusting itself to irregularities of the former.

7. In a bending-machine, the combination 20 with the swinging arm, of a shaft extending through the outer end thereof, a gear secured to the lower end thereof, a rack with which said gear engages, a gear loosely mounted upon said shaft above the swinging arm, 25 drive mechanism mounted upon the swinging arm, a pinion carried thereby which intermeshes with the gear loosely mounted upon the vertical shaft, and of means by which said gear is placed in or out of locked en-30 gagement with the vertical shaft.

8. In a bending-machine, the combination with the swinging arm, of the drive-shaft thereon, the shaft M^2 extending through the outer end portion of the swinging arm, a gear 35 loosely working thereon and driven from the drive-shaft, a clutch or friction slidably secured upon the shaft and which frictionally engages the gear, and of means by which the friction is placed in and out of frictional en-40 gagement with the gear.

9. In a bending-machine, the combination

with the swinging arm, of a forming-roller carried thereby, a former with which said roller coacts during the operation of bending, devices for holding the roller in position, 45 the drive-shaft working upon the swinging arm, the shaft M^2 extending through the outer portion of the swinging arm, a gear secured to the lower end of the said shaft, a rack with which the gear intermeshes, the gear loosely 50 working upon the shaft above the swinging arm and driven by the drive-shaft, a conical hub upwardly extending from the gear, a friction or clutch slidably upon the shaft, and of means by which the friction or clutch is 55 placed in or out of frictional engagement with the driven gear.

10. In a bending-machine, the combination with the bed-plate, of a swinging arm secured thereto, devices for locking said arm at the 60 end of its outward stroke, of means by which the swinging arm is automatically returned to its normal position upon being unlocked, of a forming-roller carried by the swinging arm, a former attached to the bed-plate and 65 with which the forming-roller coacts, and of mechanism for imparting an outward swing or travel to the swinging arm.

11. In a bending-machine and in combination with the described bending mechanism, 70 of the hydraulic press, of the formers carried by the piston thereof, and of adjustable stops for limiting the movement of the movable formers.

In witness whereof we have hereunto set 75 our hands.

JOHN T. SCOTT.

CHARLES G. HIGHTOWER.

FRANK E. NEITZEL.
